ELECTRONIC TIME PROGRAMMER
Jean J. Dorig, 1815 Walnut St., Lafleche,
Quebec, Canada
Filed Nov. 5, 1963, Ser. No. 321,633
11 Claims. (Cl. 58—150)

This invention relates generally to improvements in automatic signals and appointment reminder devices, and more particularly to an electronic time programmer that provides both audible and visual signals automatically operable at predetermined periods of time, the periods at which the signals become activated being selectively predetermined and their duration being controlled manually.

It is conventional practice for people engaged in various business and professional occupations to utilize some form of device to remind them of specific duties which need to be performed within or upon a given time, appointments which have to be kept during their working day and important activities, the commission of which is invariably related to and governed by the time of day.

The usual reminder device generally consists of a desk calendar having the typical loose leaf tear off or flip over sheet, each sheet serving for one particular day within the year and normally having ruled subdivisions imprinted thereon related to hourly or half hourly periods of the particular day. Therefore, an executive or his secretary wishing to be reminded of an appointment to be held say, for instance, at two-thirty p.m. on a given date, would enter brief particulars at the relative time period marked on the calendar.

While this method serves as a reminder device of some value, its limitations are immediately apparent. Once an entry has been made, the person involved still relies almost solely on his memory, having to refer constantly to the calendar, particularly if, as is usually the case, there is a multiplicity of appointments, duties and imperatives to be complied with during the day. Thus, an executive working on a tight schedule or a secretary having numerous duties to perform may, although some time previously having entered an appointment on the calendar, forget that such an appointment was even made, the pressure of work often being such as to divert the attention for periods of time much longer than originally anticipated.

In order to overcome the limited value of the conventional desk calendar as a reminder device, numerous alternatives have been proposed such alternatives generally involving electrical, mechanical or electro-mechanical units adapted to issue some form of warning or reminder either visual or audible at a given time period during the working day.

While such devices as have heretofore been proposed appear to fulfill their various purposes they yet suffer from certain inherent disadvantages, not least among them being their complexity of construction and consequently the relatively high cost of manufacture thereof.

Having in mind therefore, the utility of an appointment warning device of the nature heretofore described and realizing the value of such an appliance in commerce, industry and other fields of activity, it is a prime object of this invention to provide an electronic time programmer embodying means therein whereby a reliable reminder of appointments to be kept and duties to be performed is readily available.

It is another important object of the present invention to provide an electronic time programmer which utilizes a conventional electric clock and a standard yearly desk calendar of the type having a plurality of individual tear off sheets, each sheet having indicia imprinted thereon relative to time periods of the working day.

It is another object of this invention to provide an elec-

2

tronic time programmer in which the electric clock is adapted to drive a travelling spring loaded roller contact, the contact being mounted upon and operable along a pair of guide rails located immediately subjacent the left marginal hourly marks on a daily calendar sheet, the said sheet acting as an insulator between the spring loaded roller contacts, the invention particularly comprising a punch system adapted to punch a plurality of slots along the margin of the date sheets thereby permitting the roller contacts to touch each other therethrough, such engagement being adapted to create an alarm or other signal such as, for instance, a visual signal or an audible signal, such means indicating in a positive manner that an appointment is at hand or that a specific function has to be performed.

Still another object of the instant invention resides in the provision of an electronic time programmer the user of which may enter a note or written statement on the lines adjacent the time period markings of the individual date page, thereafter forming a cut-out slot within the paper at that particular location in order to ensure that contact is made between the spring loaded roller contacts to create the warning signal.

Yet a further object of the invention seeks to provide an electronic time programmer the warning means of which, namely a light and a buzzer, may be terminated manually, either singly or together.

A still further object of this invention resides in the provision of an electronic time programmer which, through the medium of a conventional bell transformer, may be operated by normal mains supply.

Still another object of the instant invention resides in the provision of an electronic time programmer of the character herein described which does not require re-setting at the commencement of each individual working day, the user thereof merely having to insert a fresh date sheet and slot the same as heretofore described.

Another object of the invention is to provide an electronic time programmer which, while embodying the above advantages and objects is yet constructed from a minimum of component parts thereby allowing of relatively inexpensive manufacture.

The aforementioned and various other pertinent objects and features of the instant invention will become more readily apparent from the following detailed description of parts and assemblies when taken in conjunction with the accompanying drawing in which like characters of reference designate like parts in the several views and wherein:

FIG. 1 is a perspective view of an electronic time programmer embodying the invention and shown with the top cover removed.

FIG. 2 is a fragmentary plan view of the invention illustrated in FIG. 1 viewed from above and showing a page of the yearly calendar block mounted in position with various punched out slots formed in the margin thereof.

FIG. 3 is a diagrammatic view of the drive mechanism from the clock to the roller contacts and the return mechanism therefor.

FIG. 4 is a part cutaway plan view of the invention seen from the underside.

FIG. 5 is a fragmented detailed view of the roller contact unit as seen from one end.

FIG. 6 is a fragmented detailed view of the roller contact unit as seen from above, and the slot punch.

FIG. 7 is a detailed side view of the slot puncher embodied in the invention.

FIG. 8 is a schematic diagram of the electrical circuit embodied in the invention.

Referring to FIGS. 1, 4 and 8 an electric time programmer generally designated by the arrow 11 includes a baseplate 12 of substantially rectangular configuration and having a circular cut-out section 13 formed therein. Baseplate 12 also has formed on one side thereof an inverted V cut-out section 14.

Baseplate 12 has, mounted on one half of its area a compartment consisting of a storage deck 12a and a date sheet line up and support assembly 15. Storage deck 12a is adapted to receive therein a conventional yearly calendar block 16, block 16 having a plurality of individual date pages each of the said pages having subdivisions of a normal working day located down the left hand margin thereof.

Mounted upon the upper edges of storage deck 12a is a rectangular, top desk plate 17, plate 17 being adapted to support a date sheet thereon and to enable notation to be performed upon the said date sheet. An inverted V cut-out section 17a, coplanar with cut-out section 14 in baseplate 12 aids in the removal or insertion of calendar block 16 as may be required.

An L shaped guide plate 18, affixed to the right hand side of desk plate 17, is adapted to line up each individual date page as it is torn off block 16 and imposed on desk plate 17.

Mounted on the remaining section of baseplate 12 is a conventional bell transformer 19, transformer 19 having an output of approximately 16 volts from a commercial A.C. mains input of 110 volts and supplying power to operate a conventional electrical clock 20 and signalling means comprising a warning lamp, and buzzer which form part of the assembly. Mounted centrally on baseplate 12 is electric clock 20, clock 20 running directly off the 110 volts supply and being in circuit at all times. Two electric magnets 21 and 22 used to operate the warning lamp 23 and buzzer 24 respectively are fitted to a support plate 25, plate 25 being mounted on the lower left hand side of baseplate 12 with lamp 23 fitted into a lamp holder 26. Lamp holder 26 is located just aft of buzzer 24 which is mounted on a plate 27, plate 27 being affixed to baseplate 12 immediately behind support plate 25, the circuit being completed through a buzzer contact bracket 28. It should be noted that electro-magnets 21 and 22 are of the mechanical self locking type when energized by means of retainer plates 29 and 30, contact springs 31 and their cooperable locking notches that form part of support plate 25.

Electro-magnets 21 and 22 may only be released manually, this being accomplished by depressing transparent push button switch plates 35 and 36 respectively, the said switch plates being mounted on hinge springs 37 and 38, springs 37 and 38 returning switch plates 35 and 36 to their normal position against inside of lever 61.

Referring now to FIG. 3, electric clock 20 has embodied therein a main drive assembly 39, assembly 39 including a circular gear wheel 40 mounted concentrically about the hour finger mechanism of the clock. An endless chain 41 disposed in a three sided configuration by means of two idler-pulleys 42 and 43 is driven by the teeth 44 of chain 41 and is adapted to perform one complete revolution every twenty-four hours. A first dog 45 is affixed to chain 41 and projects outwardly therefrom, being adapted to engage with a projection 46a on contact drive assembly 46, dog 45 on chain 41 propelling assembly 46 downwardly as indicated by arrow A during the normal eight hour working day, say for example from 9 a.m. to 5 p.m. Upon chain 41 having moved for a third of its total revolution, dog 45 will automatically disengage with assembly 46, whereafter due to a return mechanism detailed later on in this specification it returns to the top position again as indicated by arrow B, there to remain until dog 45 on chain 41 engages again sixteen hours later.

Referring now to FIGS. 1, 3, 5 and 6, contact drive assembly 46 is slidably mounted on parallel spaced rods

48 and 49, rods 48 and 49 being mounted on a carriage base 50 affixed to baseplate 12. Assembly 46 comprises a pair of roller contacts 51 biased together by means of a helical spring 52, and mounted on a U frame 53, U frame 53 being slidably operable along rods 48 and 49.

During operation roller contacts 51 are separated by and ride on each side of the left hand marginal section edge of a date page, the circuits to the two operating signals being completed by the contacting of roller contacts 51 through pre-formed slots in the margin of the date page. Assembly 46 has included therein, an electro-magnet 54 mounted on an outer U frame 55, U frames 53 and 55 having a limited freedom of movement therebetween. Electro-magnet 54 is adapted to be energized in series with the signal operating circuits and, upon becoming energized, attracts one end of U frame 53 within contact drive assembly 46, the aforementioned limited freedom allowing U frame 53 to move downwardly a small distance thereby causing roller contacts 51 to move past the slot formed through the calendar page thereby becoming insulated from each other.

Therefore, the circuits through all three electro-magnets are completed when contacts 51 are touching the cut-out slots, thereafter being almost immediately broken upon the said contacts being propelled downwardly and onto the paper. However, due to the self-locking features of the electro-magnets 21 and 22, the electric circuits to the warning lamp 23 and warning buzzer 24 remain completed until broken by the manual depression of push button switch plates 35 and 36.

Referring now to FIGS. 2, 5 and 7, in order to provide the punched out slots adjacent to the particular time when the warning signals are required to operate, a punch assembly 56 including a punch 57 and matrix 58 is slidably located on rods 48 and 49 and may be adapted to punch out slots "S" at any position below the contact drive assembly 46, up to half an hour or even closer to the time position of contacts 51.

A hingeable paper clamp 58, adapted to be located over carriage base 50, covers the complete traverse of contact drive assembly 46, and is capable of being hingeably lifted during which operation an inwardly formed section 58a engages with an extension piece 51a attached to that section bearing the uppermost of rollers 51 thereby separating roller contacts 51 and allowing the date page to be inserted therebetween. Clamp 58 has a plurality of locating pins 59 formed at each end thereof and adapted to engage with cooperable holes 60 formed in desk plate 17, thereby passing through the date page at its upper end lower left hand corners and holding it firmly in position whereafter the slot "S" may be punched and the appointments or schedules written in at the appropriate locations.

Referring again to FIGS. 3 and 6, it will be seen that the return mechanism for contact drive assembly 46 comprises a first guide pulley 80, a second guide pulley 81, a third guide pulley 82 and a storage pulley 83. A belt 84, having a reserve length coiled within storage pulley 83 passes therefrom over pulley 81 to pulley 82 and thence to pulley 80, passing thereover to be secured at its end 84a to a retainer plate 85, retainer plate 85 being affixed to drive assembly 46 and movable therewith.

Belt 84 has attached thereto a driving dog 86, dog 86 being adjacent pulley 81 when drive assembly 46 is in the uppermost location.

Chain 41 has affixed thereto a drive dog 45 as heretofore described, dog 45 being located adjacent pulley 42 when assembly 46 is in the aforementioned uppermost position. Thus, upon dog 45 having engaged with projection 46a and moved assembly 46 downwardly on the first eight hour leg of the cycle, dog 45 will disengage from projection 46a, traveling thereafter around pulley 43 and onto the second eight hour leg of the cycle. However, as assembly 46 moves downwardly, belt 84 is drawn over its respective guide pulleys 80, 82 and 81 thereby

moving dog 86 thereon to a second location adjacent pulley 82. Upon dog 45 having traversed the second eight hour leg it will contact and engage with dog 86 thereafter biasing the said dog 86 back to its initial position adjacent pulley 81, thereby drawing assembly 46 up to its top position and completing the third eight hour leg of the cycle.

Storage pulley 83 has a spring loaded axle to which the end of the aforesaid reserve length of belt 84 is affixed, the spring loaded axle taking up the slack in belt 84 as dog 86 is moved back towards pulley 81.

Therefore, assembly 46 may be set to commence its operation at say, for instance 9:00 a.m. traveling on the first eight hour downward leg to its bottom position at which location the time will be 5:00 p.m., remaining thereat for the second eight hour leg at completion of which the time will be 1:00 a.m., thereafter being moved upwardly through the third eight hour leg to its top position at which the time will be 9:00 a.m.

It will be readily understood that these time cycles are described as being typical of a normal eight hour operational day from 9:00 a.m. to 5:00 p.m.

A cover assembly 61 is detachably attached by conventional means to the clock and drive section of baseplate 12 and is adapted to shield transformer 19, clock 20, electro-magnets 21 and 22, warning lamp 23 and buzzer 24.

Located substantially centrally of said cover assembly 61 is a circular glass 62 for viewing the clock face. Two rectangular cut-out sections 63 and 64 are located directly over push button switch plates 35 and 36 respectively allowing access thereto for the purpose of breaking the circuits to warning lamp 23 and warning buzzer 24.

Power to the operation of electronic time programmer 11 is fed from a 110 volt A.C. commercial mains supply via a conventional connector and electrical lead. Clock 20 is in circuit at all times, but power to the primary winding of bell transformer 19 (the secondary winding of which supplies a low voltage for operation of electro magnets 21, 22 and 54) the warning lamp 23 and buzzer 24 may be interrupted if desired by means of a conventional single hole toggle switch 65 (shown in FIG. 4) mounted in any convenient location upon the device.

The general design of the individual parts of the invention as explained above may be varied according to requirements in regards to manufacture and production thereof, while still remaining within the spirit and principle of the invention, without prejudicing the novelty thereof.

The embodiments of this invention in which an exclusive property or privilege is claimed are defined as follows:

1. An electronic time programmer including a clock, said clock being driven by the electrical mains supply; transformer means for the reduction of said mains supply to a suitable working voltage; a baseplate for the support of said clock and said transformer thereon; roller contact means, the roller contacts of which are biased together by spring means; roller contact drive means, said drive means causing said roller contacts to travel from a first position to a second position; a main drive assembly, said main drive assembly being activated by said clock; said main drive assembly engaging with said roller contact drive means for a pre-determined period of time, thereby moving said roller contact drive means from said first to said second position over said period of time; return mechanism for the return of said roller contact driven means to said first position; guide and support means for the locating and supporting of a single sheet day calendar page, said day calendar having a plurality of sheets, said sheets each representing a pertinent day of the year; said sheets each having the hourly and half hourly time periods of a working day marked therein in left hand marginal column disposition; traverse guide means for said roller contact drive

means, said traverse means guiding said roller contact drive means parallel with said left hand margin of said calendar sheets; punch and matrix means, said punch and matrix means being mounted and operable upon said traverse guide means; said punch and matrix means being capable of punching a slot through said left hand margin of each of said calendar day sheets, said slots being punched at any time period location down said margin; said contacts of said roller contact means being insulated one from the other by means of said left hand margin of a said calendar day sheet being inserted therebetween; warning means wired in circuit with said roller contacts; first electro-magnet means for the operating of said warning means, said first electro-magnet means being brought into circuit and activated by said roller contacts contacting each other through any of said slots in said calendar day sheet; said first electro-magnet means being self-locking; means for the manual release of said electro-magnet means; second electro-magnet means, said second means causing said roller contacts to move over said slot immediately said first electro-magnet means are brought into circuit, said roller contacts receiving said marginal paper of said calendar day sheet therebetween, thereby becoming insulated one from the other; clamp means for the retention of each individual date sheet upon said guide and support means; storage means for the holding of a conventional yearly calendar block; and cover means for the enclosure of said clock, said transformer, said main drive assembly, said roller contact drive means, said first electro-magnet means, said second electro-magnet means and said warning means thereunder.

2. An electronic time programmer as defined in claim 1 in which said roller contacts include a pair of wheel-like contacts located in edge to edge relationship and capable of free rotation about their respective axes, said contacts being biased together by means of a helical spring, said spring having one end affixed to the lower of said contacts and having its other end affixed to the upper of said contacts, said upper contact being pivotable within specific limits.

3. An electronic time programmer as defined in claim 1 in which said traverse guide means include a duality of parallel spaced apart rods, said rods being mounted on said baseplate by conventional carriage support means; and said rods being located in relatively close proximity to said clock.

4. An electronic time programmer as defined in claim 1 in which said main drive assembly includes a circular gear wheel, said gear wheel being mounted concentrically about and driven by said clock's hour finger mechanism; an endless chain, said chain being disposed in a three sided configuration by means of spaced apart pulleys located on the framework of said clock; said endless chain being driven by the peripheral teeth of said gear wheel and geared to make one complete revolution during a twenty-four hour cycle, each "leg" of the said three sided configuration being equal to a period of eight hours; and said endless chain having affixed thereto a driving dog, said dog projecting outwardly therefrom.

5. An electronic time programmer as defined in claim 1 in which said roller contact drive means include a first frame member, said first member being slidably operable along said traverse guide means; said first U frame supporting said roller contacts thereon; a projecting member attached to said drive means and disposed outwardly therefrom, said projecting member being so located as to be engaged by said main drive assembly during its operable driving period.

6. An electronic time programmer as defined in claim 1 in which said return mechanism includes a first guide pulley, a second guide pulley, a third guide pulley and a storage pulley; a belt, said belt having a reserve length coiled within said storage pulley; said belt passing from

said storage pulley to said second guide pulley and therefrom to said third guide pulley, said belt passing thereover to said first guide pulley, said belt passing thereover to be secured at its end to a retainer plate affixed to said contact drive means and moveable therewith; a driving dog, said driving dog being attached to said belt and projecting outwardly therefrom said dog being adjacent said second guide pulley upon said drive means being located in the uppermost position; said drive means upon moving downwardly causing said belt to travel over said guide pulleys said driving dog moving also; said driving dog arriving at a location adjacent said third guide pulley upon said drive means having reached its lower position at the end of said pre-determined period of time, said drive means disengaging with said main drive assembly and remaining in the said lower position for a further pre-determined period of time; said driving dog of said belt being engaged by a further driving dog attached to said main drive assembly said engagement being affected at the termination of said further period of time; said engagement causing said driving dog of said belt to be biased back to its initial position adjacent said second guide pulley, thereby causing said belt to travel one said guide pulleys in such a direction as to cause said drive means to be elevated to its upper position, said elevation being affected over a third period of time; and said storage pulley having a spring loaded axle to take up the slack of said belt during this latter period of time.

7. An electronic time programmer as defined in claim 1 in which said guide and support means for the locating and supporting of a single sheet of said calendar includes a rectangular plate, said plate being located horizontally with said baseplate and in parallel spaced apart relationship thereto; and guide means thereon receiving the correct positioning of an imposed date sheet.

30

35

8. An electronic time programmer as defined in claim 1 in which said warning means include a visual light bulb warning and an audible buzzer warning.
9. An electronic time programmer as defined in claim 5 1 in which said means for the manual release of said first electro-magnet means, include push button release plates; said plate being located immediately above each electro-magnet of said electro-magnet means; and said plates being of a transparent or translucent material.
10. An electronic time programmer as defined in claim 1 in which said second electronic magnet means is housed within a U frame; said U frame being slidably operable along said traverse guide means; said U being included within said roller contact drive means and having a limited freedom therewithin; and said electro-magnet means upon becoming energized causing said roller contact drive assembly to move within said limited freedom, thereby moving said roller contacts a small but critical distance over any of said slots on said date sheet margin, thereby becoming insulated one from each other.
11. An electronic time programmer as defined in claim 1 in which said clamp means are hingedly mounted above said baseplate and immediately over said roller contacts, the upward hinging of said clamp automatically opening said roller contacts to permit easy insertion of a date sheet therebetween.
